Eggertson, Verdun, Quebec, Canada

Application October 18, 1944, Serial No. 115,840
In Canada April 26, 1944

Term of patent 14 years

(Cl. D86—10)

To all whom it may concern:

Be it known that we, (1) John Freeman and
(2) Bjarni Eggertson, subjects of the King of
Great Britain, residing at (1) Montreal, and
(2) Verdun, in the Province of Quebec, Domin-
ion of Canada, have invented a new, original,
and ornamental Design for a Fingernail Lacquer
Polishing Brush, of which the following is a spec-
ification, reference being had to the accompan-
ying drawing, forming part thereof.

In the drawing:

Figure 1 is a perspective view of a fingernail
lacquer polishing brush, showing my new design,
and

Figure 2 is an end elevational view.

We claim:

The ornamental design for a fingernail lacquer
polishing brush, as shown.
